UNITED STATES PATENT OFFICE.

SIMON W. WARDWELL, OF PROVIDENCE, RHODE ISLAND.

STITCH-FORMING DEVICE.

1,019,208.

Specification of Letters Patent.

Patented Mar. 5, 1912.

Application filed May 17, 1907. Serial No. 374,182.

To all whom it may concern:

Be it known that I, SIMON W. WARDWELL, a citizen of the United States, residing at Providence, in the county of Providence and State of Rhode Island, have invented certain new and useful Improvements in Stitch-Forming Devices, of which the following is a specification.

My invention is a novel rotary stitch forming device for sewing machines.

The purpose of my invention is to eliminate the frictional resistance incident to the contact of moving elements with other elements, and to reduce to a minimum the friction between the needle loop and the surfaces with which it must make contact as it passes the shuttle thread supply, thereby removing influences which usually affect and disturb the tension of the thread.

A further purpose is to avoid the use of oil in the stitch forming device or on its thread engaging parts.

The accompanying drawings, forming part of this specification, represent, respectively, Figure 1, a front view of one embodiment of my invention; Fig. 2, a side view; Fig. 3, an enlarged sectional view on line *a—a* of Fig. 1; Fig. 4, a perspective view of the bowl; Fig. 5, a sectional view of the carrier; Figs. 6, 7, 8 and 9, details of the retainer and means for securing same in carrier; Figs. 10 to 27 inclusive are diagrammatic, showing the manner in which the stitch is formed. Figs. 28 and 29, illustrate a modification.

The stitch forming device comprises three members, viz.: a rotating bowl or case 2, which revolves the hook 21 to conduct the needle loop through the stitch forming process, a carrier 3 within the case 2, in rolling engagement therewith and rotated thereby, and a non-rotatable retainer 4 within the carrier to hold the shuttle thread supply, such as a bobbin, or the cop 15 with in the carrier, restraining it from rotation due to the movement of the carrier and permitting rotation due to draft of the thread in forming the stitch. Operating in conjunction with the above enumerated elements of my invention is the need 15, and there is also indicated the cloth plate 6—see Figs. 1 and 2. The arrangement of these

parts is best indicated in the sectional view Fig. 3, where, as shown and as indicated by its name, the bowl or case 2 has a bowl-shaped cavity 7, cylindrical for a short distance and then contracted convergently to the back, which is the bottom of the bowl. To this bottom or back 8 is secured the shaft 9 which rotates in the bearing 10. In external form the bowl 2 is of cylindrical periphery for a short distance from its rim 20 backward, and then converges backward in frusto-conical form to the bottom or back 8. In the rim 20 of the bowl is formed a hook 21 whose throat 22 extends diagonally from the rim 20 across the periphery 23 to near its opposite edge. As may be seen from Fig. 2, and Fig. 4, the terminus of the hook's throat is a substantial distance from an annular groove 11, to be later defined. The working point of the hook 21 is on the front of the bowl rim 20 with its extremity 29 adjacent the periphery of the rim. On the opposite side of the opening 30 of the hook, the inner edge of the rim 20 is cut away at 31 to form a clearance for the thread when the loop is withdrawn from the hook as afterward explained. In the periphery 23 is formed a groove or channel 24 which extends diagonally from the throat 22 of the hook 21 to the edge of the rim 20. In the interior cylindrical surface of the bowl and near its edge is formed the groove 11 referred to, extending around the interior of the bowl, and in this groove, held by its walls, lies a projection or flange 12 of the carrier 3. The carrier 3 also is a hollow member, as indicated by Fig. 5, having a thin, peripheral flange 12, which, as just described, seats in the internal groove 11 withholding, by its engagement with the walls of the groove, the carrier 3 from displacement and from engagement with the bottom of the bowl 2, thus leaving a free and unobstructed passage behind the carrier. The flange 12 is of such diameter as to just enter the cylindrical portion of the bowl's interior, and in this entering position is concentric with the bowl. When in place, however, with its flange dropped into the track or groove 11, the carrier is slightly eccentric to the bowl 2, and when the latter rotates, the carrier also rotates, just as a spur gear would ro-

tate in mesh with an internal gear, only here there are no teeth required, for the transmission of the bowl's rotation to the carrier is due to the frictional engagement of the two, superinduced by the weight of the carrier 3 and its contents, which mode of transmission is adequate and preferable. The depth of the groove 11 and the height of the flange 12 are such that when the carrier 3 is in place, a crescent-shaped space or opening 27 is formed between the periphery of the flange 12 and the inner surface of the bowl 2. This opening provides a passage through which a portion of the needle 15 thread enters the interior of the bowl, and passes around the carrier 3 to form the stitch. The location of the widest part of this opening is normally at the top, near the needle thread, dependent on the radial position of the carrier 3, as governed by said thread, all of which will be later explained. The body of the carrier 3 extends backward with a sloping or frusto-conical form from the flange 12 to the back or bottom of the carrier. The distance from the edge of the flange 12 to the base of the frusto-conical back portion is slight. The front of the carrier 3 protrudes from the bowl 2 with rounded, bulging form, and the distance from the base of this bulge to the edge of the flange is substantially greater than the corresponding distance at the back of the flange. The outward protrusion of the carrier balances the latter's inward, frusto-conical formation, making the carrier's sectional form at a plane intersecting its axis, substantially lenticular and symmetrical with a line passing through the needle. The purpose of this formation is to cleave or divide the loop, in passing the carrier, equally to either side of the needle line, as will be further explained when the stitch formation is analyzed.

Within the interior of the carrier 3 is a post or stud 13 integral with or secured to the carrier's bottom, and the said post has near its extremity a peripheral groove 14 for purposes to be defined later. Mounted on this post is the retainer 4 which is preferably of the form indicated in Fig. 6, substantially semi-circular in its bottom part, below the point of suspension or mounting, and above this having an arm 16 which projects across the end of the cop and beyond its periphery or face, and then across the said face, and having a sleeve 17 by which it is supported on the post 13. This form and arrangement establishes the retainer's center of gravity below its center of suspension, causing it to ride upright and resist any tendency to be rotated, by the rotating carrier 3, through the stud 13. This resisting effect could be still further increased by enlarging the bottom part of the retainer, as

for example, extending it beneath the thread supply, as shown in Figs. 28 and 29. I prefer, however, to drop the center of gravity of both the retainer and its thread mass below their center or axis of suspension, and accomplish this in the following manner: The sleeve 17 by which the retainer 4 is mounted on the post 13 has an eccentric bore and is so secured to the retainer that its bore is concentric with the latter's semi-circular part. The outer, cylindrical surface of the sleeve 17 is therefore eccentric to the axis of suspension of the retainer, which is likewise the axis of rotation of the carrier 3, and as the cop or shuttle thread supply is carried on the exterior cylindrical surface of the sleeve, it likewise is eccentric to the axis of rotation of the carrier 3, and hangs pendulously down, as does also the retainer itself, because the center of gravity of the mass is below its center of suspension. This ballasts or "trims" the retainer and its thread mass, causing both to ride evenly and upright, and resist any tendency to rotate with the carrier 3. Further, this resistance is of elastic or yielding character. While it suffices to prevent the thread supply from rotating, it can yield rotatively under sudden or extraordinary influence, recovering its poise gradually under action of gravity, thereby accomplishing the highly desirable function of delivering a thread which is constantly uniform in tension and consequently a resultant stitch of great regularity and evenness. As is indicated in Figs. 1 and 2, any tendency of the retainer to rotate, due to draft of thread therefrom, is prevented by the thread drawing through the eye 16^a in the arm 16, or the thread might be simply led up across the arm to prevent such rotational tendency. The cop 15, itself, rotates on the sleeve 17 to deliver thread to the stitching.

The retainer 4 is held on the post 13 by the spring clip 18 which lies in the groove 19 of the eccentric sleeve 17. This groove is sufficiently deep to cut across the eccentric axial hole of the sleeve 17, and is so located, registering with the groove 14 of the post 13 when the retainer 4 is in position in the carrier 3, that the ring 18 serves as a lock. Little retaining resistance is required to hold the retainer in position, so that the spring ring 18 requires but little constrictive elasticity and therefore the retainer 4 can be easily pushed on or removed from the post 13.

Having now particularly described the component elements in form and inter-relation, I will describe their coaction with the needle 5, and to most clearly effect such description, present six sets of diagrammatic views, each set depicting the relation of the loop to the bowl 2, to the carrier 3 and to

both, in six different phases of the stitch forming process.

The needle when lifted is poised above the bowl 2 (Figs. 1 and 2) and in such position that in its down movement it passes directly by and close to the ring 20 and, when the hook 21 catches the needle loop, the latter is drawn inward past the plane of the groove 11, and therefore well across the flange 12 of the carrier. As the needle descends (Fig. 12) opposite the rim 20, the hook 21 catches the needle loop 26 and draws it into the loop throat 22 (see Fig. 10). In so doing, the portion 26^a of the needle loop is led to the channel 24 and the portion 26^b of the loop is drawn in between the bowl 2 and the carrier 3, through the opening 27 and across the flange 12, Fig. 11. Hereafter, to further identify in the drawings the two portions of the loop, the portion 26^a will be shown dotted, and the portion 26^b in a dot-dash line. As the bowl 2 turns, (Fig. 13) revolving the hook 21, the loop portion 26^a follows the channel 24; (Fig. 13) while the lower loop portion 26^b draws over and then lies outside of the flange 12, (Fig. 14) due to the throat 22 Fig. 4 extending well toward the inner side of the flange 12. Further rotation of the bowl, as indicated by Fig. 18, causes the loop portion 26^a to drop over the edge of the carrier 3 (Figs. 16 and 18). The other loop portion 26^b, as indicated in Fig. 17 being within the bowl, falls on the inclined back of the carrier. Still further rotation, indicated by Figs. 19, 20 and 21, cleaves or spreads both portions of the loop 26 apart, the portion 26^a falling on the bulging outer face of the carrier 3, and the portion 26^b falling on the conical back portion of the same element. This stage is the commencement of the passage of the loop 26 by the carrier 3, the loop 26 being drawn by the revolving hook 21 past the said carrier. As the hook revolves, the loop portion 26^a clings for a time to the protuberant front and the loop portion 26^b to the conical back of the carrier, so at first that the action is similar to that of a cord run onto the periphery of a wheel or sheave both moving at the same speed. Then, after a certain period of advance of the hook 21, the two portions of the loop 26^a and 26^b fall or drop over the front and back, respectively, of the carrier 3. This rolling action of the carrier, with the revolving of the hook 21, carries the loop to the position indicated by Figs. 22, 23 and 24. This combined leading action of the hook 21, with the rolling, conveyer action of the carrier 3, which rolls through the loop, draws out such extent of loop that when the latter, in its two parts, falls over the front and back of the carrier, so loose is its tension that there is no friction in its passage over the

latter. The smooth, bulging face of the carrier 3 and its continuation or complement in the face of the retainer 4, together with the conical back of the carrier, lend to the ease of passage of the loop 26 past the carrier, because their smooth, polished surfaces are so formed as to present no obstruction.

Figs. 22, 23 and 24 show the loop after it has passed by the carrier 3. As the hook 21 passes by the vertical center the tension of the take-up tends to draw the loop 26 out of the hook 21, and the loop then bears on the rim 20 of the carrier 3—see Fig. 24. Here appears the function of the clearance 31 on the rim 20, before described, permitting the loop to be readily withdrawn and relieving it of the pinching which would otherwise occur between the carrier and the bowl, so that after the stitch is formed, the loop can be taken up freely by the take-up without restriction.

Figs. 25, 26 and 27 show the stitch-forming operation completed, the loop 26 having passed completely around the retainer 4 which contains the shuttle's thread supply, and now being free to be drawn up through the cloth.

The reason for the slight distance from the edge of the flange 12 to the base of the frusto-conical portion of the carrier must now be apparent. As the loop bottom 26^b enters between the bowl 2 and carrier 3 from the rim 20, there is a natural tendency for it to pull out, instead of over behind the carrier 3; but the quick engagement with the tapered body of the carrier causes a quick cleaving or splitting of the loop, and also causes the thread to travel across the flange and over back of the carrier, as desired. The more extensive space on the part of the carrier 3 from the edge of the flange 12 to the base of the bulge is to make room for the point of the needle. In brief, the bowl 2, with its hook 21, constitutes a conducting element which engages the needle loop and leads it around the shuttle thread supply. The carrier 3 performs a four-fold function: first, as a vehicle or container for the shuttle thread supply; second, as a conveyer for carrying the loop as it is led by the hook 21 during part of its passage around the shuttle thread supply, and, then, third, as a cleaver and guard to split the needle loop and pass it to either side of and by the shuttle thread supply, avoiding its contact therewith; and, fourth, as an anti-friction intermediary between the rotating bowl and the stationary thread supply retainer within the bowl. Because of this construction, no oil is required on or in the thread manipulating parts, thus removing liability to oil stains and obviating careful attention to their lubrication. In effect, the shuttle

thread supply and its adjuncts are mounted antifrictionally within the case or bowl which carries the looping hook.

As the stitch forming process consists in passing the cop case and its contents through the loop 26—or vice versa—it has not appeared essential to depict the thread led from the cop within the shuttle in these diagrammatic views. Such delineation would, rather, be detrimental, confusing the views and lending no force to the explanation.

I believe myself the first to devise a stitch forming mechanism having a rotatable support, a carrier situated within the support and rotated therewith, and a non-rotatable thread retainer situated within the carrier, and therefore, I desire to claim same broadly, without limitation as to the specific forms or arrangements employed.

What I claim is:

1. In a stitch forming device for sewing machines, the combination with a needle for the upper thread and a flanged carrier for the lower thread supply, of a rotating bowl having a hook to engage the needle loop and present it to the lower thread supply and also having a track within its interior in which track the carrier rolls by its flange which alone, without other agency, restrains the carrier from axial movement, maintaining free passage for the needle loop between the carrier and the bottom of the bowl as well as past the outer end of the carrier, the latter rolling over the bottom portion of the loop which extends across the track, in the formation of the stitch.

2. In a stitch forming device, the combination with a rotating bowl having a hook and an internal track, of a carrier held to the track by a flange and rolled in the track by rotation of the bowl and held within the bowl and withheld from axial movement with relation to the bowl by engagement of the flange and track and by no other agency.

3. In a stitch forming device, the combination with a rotating bowl having a hook, of a carrier retained within the bowl and withheld from axial movement relative thereto by engagement with the interior of the rim of the bowl and rotatively driven by said engagement.

4. In a stitch forming device, the combination with a rotating bowl having a hook to engage the needle loop, of a carrier to spread the loop mounted within the bowl and rotatable therewith and having a surface protruding without the bowl, upon which surface a part of the needle loop is drawn and which by its rotary movement propels said loop along as the latter advances to the point where it is spread to pass the carrier.

5. In a stitch forming device, the combination with a rotary bowl having a hook to engage the needle loop, of a carrier for the under thread supply mounted within the bowl and rotated thereby, and having a portion protruding without the bowl upon which portion part of the needle loop is drawn and which moving with the needle loop helps to propel the latter past the lower thread supply.

6. In a stitch forming device for a sewing machine, the combination with a rotating bowl and a carrier mounted eccentrically within the bowl and having within itself a central post, of a retainer hung pendulously thereon by an eccentric sleeve.

7. In a cop retaining device for sewing machine shuttles, the combination with a post having a peripheral groove in its outer end, of an eccentrically bored sleeve having a peripheral groove which intersects the bore of the sleeve and which groove registers with the groove of the post when the parts are in position, and a spring clip in the groove of the sleeve to engage the groove of the post, as described.

8. In a thread supply retainer for a sewing machine, a substantially semicircular, dished plate, having an arm to project across the thread supply to engage the outgoing thread and prevent rotation of the retainer, and an eccentrically bored sleeve to support the thread supply.

9. In a stitch forming device, the combination with a rotating carrier for the shuttle thread supply, of a bowl 2 rotatively engaging the carrier, and without which a rotating surface of said carrier protrudes, a hook thereon, and provided with a throat extending diagonally across the periphery of the bowl, and having a clearance 31 formed at the inner edge of the bowl's rim, as described.

10. In a stitch forming device, the combination of a rotating bowl, a carrier within the bowl, rotated by rolling engagement with the rim of the bowl, and maintained by engagement with said rim from making and engagement with the bowl, and a thread retainer connected therewith and supported and constructed to remain stationary by gravitation.

11. In a stitch forming device, the combination with a needle for the upper thread, of a rotating bowl with a hook adapted to engage a loop of the needle thread, an auxiliary member rolling within the bowl and protruding therefrom to receive and carry said loop, and a retainer for the under thread connected to and within said auxiliary member and withheld by gravity from rotating with said auxiliary member.

12. In a stitch forming device, the combination with a needle for the upper thread, of a rotating member having means to draw

the thread from the needle, an auxiliary member riding within and maintained axially by said first member, an under-thread retainer connected with the auxiliary member and maintained non-rotating by gravity, and means to actuate said mechanism to form the desired stitch.

In testimony whereof I affix my signature in presence of two witnesses.

SIMON W. WARDWELL.
